UNITED STATES PATENT OFFICE.

ALBERT J. ARMSOM, OF PORT HURON, MICHIGAN, ASSIGNOR TO THE ARMSOM EXHAUST HEATING COMPANY, OF CLEVELAND, OHIO, A CORPORATION OF OHIO.

EXHAUST-TREATING APPARATUS FOR STEAM-POWER PLANTS.

Application filed March 14, 1925. Serial No. 15,672.

This invention relates to an exhaust treating apparatus for steam power plants such as are employed on steamboats, especially those plying fresh water lakes, as the Great Lakes, 5 plants of this kind having a main engine for propelling the boat and a large number of auxiliary engines.

More particularly the present invention is an improvement on the exhaust treating apparatus constituting the subject matter of my prior application, Serial No. 613,932, filed January 20, 1923.

As stated in my application above referred to, in steam plants on boats, such as those plying the Great Lakes, it has been customary to lead the exhaust steam from the main engine direct to a jet condenser and to pump the boiler feed water from a well into which the condenser water is pumped, and to heat the feed 15 water by the exhaust steam from the auxiliary engines, this exhaust steam after being passed through the heater being discharged to atmosphere. It might be mentioned that on boats of this kind many auxiliary engines 20 are employed, such as those used for pumping water ballast, electric lighting, mooring, etc.

The apparatus constituting the subject matter of my prior application was designed to effect certain economies in the exhaust 25 treating method commonly employed by utilizing more effectively than before, the heat in the exhaust steam from both the main and auxiliary engines, and by reducing the amount of waste heat and also increasing the 30 efficiency of the condenser part of the plant.

This was accomplished in accordance with my prior invention by introducing between the condenser and the exhaust pipes of both the main and auxiliary engines, a chamber, 35 the steam from the main and auxiliary engines being passed through this chamber and then to the condenser, and the feed water being pumped from the condenser through pipes extending substantially the length of 40 the chamber, then past a settling chamber, and then to the boilers.

The object of the present invention is to effect still greater economies, and particularly to increase still further the temperature of 45 the feed water by a novel method of exhaust treatment with the exhaust steam of both the main and auxiliary engines.

Briefly stated, by the present method the

exhaust from the main and auxiliary engines instead of being passed through one main feed 55 water heating chamber is passed through two separate heating chambers, or through different compartments of the same chamber, and then the exhaust steam from both chambers, or from both compartments is condensed, 60 preferably, though not necessarily, in a single condenser, but arrangement is made so that the pressure reducing, and therefore, the temperature reducing action of the condenser does not affect the steam in the chamber 65 receiving the exhaust from the auxiliary engines. In consequence, by passing the feed water first through the chamber which receives the exhaust from the main engines, and then through the chamber receiving the exhaust from the auxiliary engines, which exhaust is at a higher pressure, and therefore at 70 a higher temperature than the exhaust in the first chamber, the temperature to which the feed water is raised by the exhaust treatment is materially increased.

The invention may be further briefly summarized as consisting in certain novel details of construction, and combinations and arrangements of parts which will be described 75 in the specification and set forth in the appended claim.

Referring now to the drawings wherein I have shown the preferred embodiment of the invention, Fig. 1 represents diagrammatically 80 or conventionally, a portion of a steam plant involving my invention, but omitting those parts such as the main and auxiliary engines and boilers, which are not essential to an understanding of the invention; Fig. 2 is a 85 sectional view substantially along the line 2—2 of Fig. 1; Fig. 3 is a section substantially along the line 3—3 of Fig. 1; and Fig. 4 is an enlarged detail sectional view showing the packing for the water tubes in the 90 headers or transverse partitions.

In the drawings, 10 represents a pipe which conveys the exhaust steam from the main engine (not shown), this pipe being connected to a valve casing 11, which is in the nature 100 of a shut-off valve. This casing has an outlet 12, leading down to a horizontally disposed drum 13 wherein the feed water is heated and the temperature of the exhaust steam is reduced, as will be explained presently. This 105 drum is provided between its ends with a

transverse partition 14 dividing it into two separate compartments or chambers A and B. The chamber A is preferably longer than the chamber B, and it is to this chamber that the 5 exhaust from the main engine is introduced.

The exhaust from all the auxiliary engines (not shown) of the plant is led to chamber B, the exhaust being introduced at a suitable inlet indicated at 15. Near the outer end of 10 chamber A there is a tube sheet 16, and between the header and the adjacent end of the chamber, feed water is introduced by a pipe 17, which will be referred to presently. Near the outer end of chamber B there is a tube 15 sheet 18, and beyond the header a baffle 19, under the lower edge of which the heated feed water passes over a connection 20 with a settling chamber 21. Also located beyond the baffle 19 between the latter and the adjacent 20 end of drum 13 is an outlet 22 for the feed water, this outlet being designed to be connected by suitable piping to the boilers (not shown).

Extending horizontally through the chamber A is a partition 23, near one end of which is an opening 23^a, so that the exhaust steam from the main engine is required to pass for practically the full length of the chamber A, first above and then back along the lower side 25 of this partition. In chamber B there is a similar horizontal partition 24 which extends from the tube sheet 18 substantially to the partition 14, so that the exhaust steam from the auxiliary engines will pass for substantially 30 the full length of the compartment B, first above the horizontal partition 24, then down through a space between the end of the partition 24 and the vertical or transverse partition 14, and back along beneath the 35 partition 24.

Extending horizontally through drum 13, between the headers 16 and 18, and communicating with the spaces between the tube sheet and the adjacent ends of the drum are 40 a series of horizontal feed water tubes 25, which are located both above and below the horizontal partitions 23 and 24. As will be obvious, the exhaust steam from the main engine in passing along chamber A, first in one direction above partition 23, and then in 45 the opposite direction beneath partition 23, and the exhaust steam from the auxiliary engines in passing similarly through chamber B surrounds the feed water tubes 25 and 50 heats the water passing through the tubes, the temperature being elevated a certain amount in chamber A, and being raised still higher in chamber B, as will be explained presently. The exhaust steam after passing 55 through both chambers A and B is condensed, and though separate condensers might be employed, I prefer to use a single condenser for the steam conducted from both chambers A and B. The condenser referred to, is shown 60 at 26, this being a jet condenser which may 65

be of usual construction, the water for condensing the steam being introduced through a pipe 27.

Chamber A has an outlet 28, which is connected to a T-fitting 29 leading to the condenser 26, a direct connection being made so that a partial vacuum is produced in chamber A. Chamber B has an outlet 30, and this outlet is also connected to the fitting 29, and therefore to the condenser, but between the outlet 30 and the fitting there is introduced a so-called back pressure valve 31, the same being arranged in piping 32 connected at one end to the outlet 30, and at its other end to the end of the T-fitting 29. The effect of this 70 back pressure valve is to maintain in chamber B the same pressure that would exist if the condensing feature were not introduced to the exhaust from the auxiliary engines. In other words, the same pressure exists in this 75 chamber B as if the steam from outlet 30 were conducted to atmosphere. The pressure in this chamber is therefore above atmospheric, and in practice the gauge pressure is about 80 ten pounds, i. e. ten pounds above atmospheric. This means that the temperature of the steam in the compartment is considerably 85 above 212°, and in practice is about 250° F. On the other hand, since chamber A is 90 direct connected to the condenser, the pressure is below atmospheric, as previously stated, and therefore the temperature is below 212° F.,—in practice, in the vicinity of 155° F. 95

It is to be noted that the back pressure valve 31 is paralleled by piping 33, having a shut-off valve 34, which is ordinarily closed, particularly when the main engine is in operation, but in the event the steamboat is in port, and the main engine is idle, and in the event the auxiliary engines are being used extensively, valve 34 may be, and generally will be opened so as to in effect convert the auxiliary engines to condensing engines so as to remove the back pressure and enable them to work at maximum efficiency. This, of course, 100 reduces the pressure and temperature of the exhaust steam in chamber B, and reduces the temperature to which the feed water is raised, but it will be understood that at such time the main engine is not in operation, and high temperature feed water is not so essential. 105

The condenser water is preferably conducted from the condenser and supplied to the feed water tubes 25, as in my prior application,—that is to say, it is conducted by a pipe 110 35 to a so-called air pump 36, generally operated from the cross-head of the main engine, and is pumped to a chamber 37, from which the water is pumped by a feed water pump 38 to the pipe 17, the intake side of the pump being connected by pipe 39 to the chamber 37. 115

A separate pump 40 is provided for operation when the main engine is not working, and the air pump 36 not operated; this pump 120 having its intake connected to the condenser 125

by a pipe 41, and its outlet connected by a pipe 42 to the discharge pipe 43 which normally discharges the excess water from the condenser overboard, this pipe being connected 5 to chamber 37 as indicated.

The feed water tubes 25 are preferably fitted without packing in the tube sheet 16, but in the transverse partition 14, and in the tube sheet 18 the tubes are preferably packed, 10 as indicated in Fig. 4, the packing being preferably retained in partition 14 by a pressure plate 44, and the packing in tube sheet 18 preferably includes a separate gland or packing nut 45 for each tube, as indicated in Fig. 15 4. This packing takes care of the difference of pressures in the two chambers on opposite sides of the partition 14, i. e. between the higher or super-atmospheric pressure in chamber B, and the pressure in chamber A 20 below atmospheric, and also it takes care of the very considerable difference in pressure existing on opposite sides of the header 18, due to the high pressure at which the feed water is supplied to the boilers.

25 It should be noted also, that by mounting the packing of the tubes as indicated in Fig. 4, the tubes may expand and contract freely, this being of importance in view of the rather great length of the tubes.

30 As stated above, under normal conditions the hand-operated by-pass valve 34 is closed, and the back pressure valve 31 effective so as to get the high temperature heating effect in chamber B, but when the boat is in port and 35 the main engine idle, and when it is desired that the auxiliary engines be worked at highest efficiency, the auxiliary engines are operated as condensing engines by opening the valve 34. As stated above, this reduces the 40 temperature of the feed water somewhat, but this is compensated for by the fact that the auxiliary engines are thus operated at higher efficiency, and whereas under usual practice the steam from the auxiliaries is discharged 45 direct to atmosphere and the heat therein is lost, with this system all the exhaust is brought back to a central point, and the heat is largely saved.

It will be seen therefore, that with the present 50 improvements, with the plant operating normally, the temperature of the feed water is elevated to a higher degree than with the apparatus shown in my prior application.

A further advantage lies in the fact that 55 inasmuch as the feed water is elevated to a higher temperature before leaving the chamber 18, cleaner water is delivered to the boilers,—that is to say, more sediment will be deposited in the settling chamber than with 60 the apparatus which delivers the feed water at a lower temperature. This condition reduces the abrasive quality of the steam, and therefore requires less oil than under conditions wherein dirtier water and more sediment 65 were conducted to the boilers.

Additionally it might be stated that inasmuch as a maximum amount of the heat in the exhaust steam is extracted or absorbed by the feed water, particularly as the heating by the steam in chamber B is under pressure and temperature conditions comparable with non-condensing engines, although the pressure, and therefore the temperature is immediately reduced after passing the back pressure valve, there is nevertheless a reduction in the amount of water required to be supplied to the condenser, and therefore there is a smaller amount of water which is dumped overboard after being pumped from the condenser, and therefore a less waste of 70 heat at this point.

75 It will be seen, therefore, that with the improvements herein described, economies are effected to an important degree, and therefore the object of the invention stated at the beginning of the specification is attained 80 very effectively.

85 While I have shown the preferred construction, I do not desire to be confined to the exact details shown, but aim in my claims to cover 90 all modifications which do not involve a departure from the spirit and scope of the invention as set forth in the appended claims.

Having described my invention, I claim:

1. In a steam power plant of the type having 95 a main engine and a plurality of auxiliary engines adapted to be supplied with steam from boilers, pipes for delivering exhaust steam from said engines, condensing means, heating chambers between said pipes and the condensing means, one of said chambers receiving exhaust steam from the main engine and the other of said chambers receiving exhaust steam from the auxiliary engines, means between the condensing means and the chamber 100 receiving steam from the auxiliary engines for maintaining in the second chamber relatively high temperature and pressure conditions, and feed water pipes extended through said chambers and adapted to be connected to the boilers.

105 2. In a steam power plant of the type having 110 boilers, a main engine and a plurality of auxiliary engines, pipes for delivering exhaust steam from the main and auxiliary engines, chambers to which said pipes are connected, condensing means, means connecting each of said chambers to the condensing means, a back pressure valve in the connection between said condensing means and the 115 chamber receiving the exhaust from the auxiliary engines, and means for passing feed water successively through said chambers.

120 3. In a steam power plant of the type having 125 one or more boilers, a main engine and a plurality of auxiliary engines, condensing means, pipes for conducting exhaust steam from the main and auxiliary engines, feed water heating compartments between said pipes and the condensing means and connect- 130

ed thereto, a back pressure valve in the connection between the condensing means and the compartment receiving steam from the auxiliary engines, a by-pass for rendering said back pressure valve ineffective, and means for passing feed water through both compartments successively.

4. In a steam power plant of the type having boilers and a plurality of engines receiving steam therefrom, jet condensing means, two feed water heating compartments, means for supplying to one compartment low pressure exhaust steam from one engine, means for supplying to the other compartment relatively high pressure exhaust steam from another engine, means connecting the outlets of

said compartments to the condensing means, back pressure means between the condensing means and the chamber receiving relatively high pressure exhaust steam, feed water tubes extending through the compartments, and means for pumping water warmed by the condensing means, through said tubes, whereby the temperature of the feed water is elevated in one compartment and is still further elevated in the second compartment, the latter receiving the relatively high pressure steam. 20 25

In testimony whereof, I hereunto affix my signature.

ALBERT J. ARMSON.
